UNITED STATES PATENT OFFICE.

EDWARD W. ISOM, OF LOCUST VALLEY, NEW YORK, ASSIGNOR TO SINCLAIR REFINING COMPANY, OF NEW YORK, N. Y., A CORPORATION OF MAINE.

ART OF CRACKING HYDROCARBON OILS.

Application filed June 19, 1925. Serial No. 38,128.

To all whom it may concern:

Be it known that I, EDWARD W. ISOM, a citizen of the United States, residing at Locust Valley, in the county of Nassau, State 5 of New York, have invented certain new and useful Improvements in the Art of Cracking Hydrocarbon Oils; and I do hereby declare the following to be a full, clear, and exact description of the invention, such 10 as will enable others skilled in the art to which it appertains to make and use the same.

This invention relates to improvements in the cracking of heavier hydrocarbon oils, 15 such as gas oil or kerosene, to produce lighter hydrocarbon oils, such as gasoline or pressure distillate, therefrom. This application is in part a continuation of my prior application filed August 28, 1922, Serial No. 584,711.

The invention relates particularly to improvements in the construction and operation of externally heated tubular single pass oil cracking stills or in cracking still systems 25 in which externally heated tubular single pass heaters are employed. The invention includes improvements in both method and apparatus.

When hydrocarbon oils are heated to 30 a cracking temperature, they are decomposed with the formation of lighter hydrocarbon oils. The products of the cracking reaction also include a certain amount of fixed gases and heavy tar or pitch or carbon. When the 35 cracking is effected by external heat transferred to the oil through the walls of heating tubes, the carbon or tarry matter tends to deposit on the heating surfaces in contact with the oil and to form an insulating layer 40 thereon which retards heat transfer. Not only does this deposit impede the effective transfer of the heat to the oil, but it also deprives the walls of the heating tubes of the protective effect of the oil which tends to 45 reduce the temperature of the tube walls by absorbing heat therefrom. The result is a tendency toward increase in temperature of the tubes, as compared to the oil passing therethrough, which accelerates the deposition 50 and tends to bake the deposit to a dense closely adherent mass further increasing the temperature of the tubes. This tendency imposes a danger of rupture due to overheating and is usually the limiting factor 55 both in the life of the heating tubes as well

as in the period over which the operation can be continued in a single run. The heating tubes nearest the fire-box and first exposed to the fresh products of combustion are subjected to the most severe conditions, and the 60 most easily cracked oils tend to cause the greatest deposit of carbonaceous material under any given conditions. The rate of deposition with any one oil also increases rapidly as the temperature to which the oil 65 is subjected exceeds that required to effect the desired cracking.

In externally heated single pass tubular oil cracking stills or heaters, the oil is passed but once through the oil heating tubes and 70 the entire heat input to the oil is effected in a single passage of the oil through the heating tubes, the oil supplied to the still being brought from its initial temperature to the desired cracking temperature in the single 75 passage of the oil through the heating tubes. In referring to single pass heaters, I refer to stills in which fresh oil is circulated but once through the oil heating tubes and include stills where vaporized fractions of the 80 oil are refluxed and recirculated through the heating tubes, but I exclude stills in which the fresh oil itself or any unvaporized portion thereof is recirculated through the heating tubes. In such stills it is desirable, for 85 efficiency of operation and economy of equipment, to transfer the maximum amount of heat to the oil in a minimum distance of oil travel, and at the same time to avoid overheating of the still tubes and other 90 severe strains on the still equipment. Hitherto, these apparently contrary factors have prevented development of maximum heating efficiency in externally heated single pass tubular oil cracking stills. For 95 example, proposals have been made to use relatively low furnace temperatures reducing the temperature of the hot products of combustion by dilution with cold air or by carrying out the combustion with a large 100 excess of air, but these have involved the sacrifice of fuel efficiency and resulted in large fuel consumption.

This invention provides an improved arrangement of this type of cracking still and 105 a new method of operating cracking stills of this general character in which the heating tubes are protected while high heating efficiency is secured. The invention also provides an improved way of handling reflux 110

in externally heated single pass tubular cracking stills. Other features and advantages will appear as the description proceeds.

- 5 According to the present invention, the vapors of the cracked oil discharged from the single pass heater are subjected to a refluxing operation and the reflux therefrom is circulated through the tubes of the heater, 10 fresh oil being supplied to the heater at an intermediate point, and the hot products of combustion from the fire-box are circulated over the tubes of the heater in generally concurrent relation with the oil flow. The 15 heating gases thus first contact with the heating tubes through which the refluxed oil is circulating and then contact, after being reduced in temperature by the heat absorption on these initial tubes, with the heating tubes through which the fresh oil is circulating in admixture with the reflux. The reflux is relatively refractory and assists in tempering the heating gases without excessive carbon formation and at the same 20 time is subjected to high temperatures which assist in cracking it with the production of the desired lighter products. The fresh oil is then subjected to the milder heating action of the tempered heating gases, and the 25 hot products discharged from the initial heating tubes into the heating tubes through which the fresh oil is circulated also assist in heating the fresh oil internally as admixed therewith. The initial heating tubes 30 are thus employed to temper the heating gases while they are protected by circulation of relatively refractory stock therethrough and the latter tubes are protected by this tempering of the heating gases. A part 35 of the heating gases escaping from the heating furnace may be recycled over the heating tubes with the fresh products of combustion to further assist in protecting the heating tubes and improving the cracking operation. 40 The single pass heater may be arranged to discharge into a vaporizing chamber or reservoir, which may be heated externally or which may be heated internally only by the 45 hot products discharged from the single pass heater, and to which additional fresh oil 50 may or may not be supplied.

The invention will be further described in connection with the accompanying drawings which illustrate in a diagrammatic and conventional manner apparatus embodying the invention and adapted for carrying out the invention, but it is intended and will be understood that this further description and illustration are for the purpose of exemplification and that the invention is not limited thereto.

In the accompanying drawings:

Fig. 1 diagrammatically represents, partly in elevation and partly in section, one form 65 of apparatus embodying the invention and

adapted for carrying out the process of the invention, and

Fig. 2 is a diagrammatic illustration of the process and of the operation of the apparatus of the invention in the nature of a 70 flow sheet.

In the drawings a single pass externally heated tubular still is shown discharging into a shell still or a reservoir from which vapors of the cracked oil are taken off. The 75 single pass heater comprises a furnace 1 in which a battery of heating tubes are arranged. The battery is made up of two sets of tubes, 2 and 3, connected at 4. A connection 5 is arranged for supplying oil to the set of tubes 2 whence it is discharged into the set of tubes 3 through connection 4, another connection 6 being arranged for supplying oil at this intermediate point. After passing through the battery of heating tubes in a single pass, the oil supplied through connections 5 and 6 is discharged 80 into the reservoir 8 through connection 7. The heating furnace 1 is provided with a fire-box 9 and a stack flue 10, heating gases 90 being circulated from the fire-box first over the set of tubes 2 and then over the set of tubes 3 to the stack flue. The fire-box is provided with means for burning the fuel employed to supply the heat used in the cracking operation. A burner for gaseous or liquid fuel is shown at 11. A return connection 12 provided with forcing means 13 is arranged for withdrawing heating gases 95 from near the outlet to the stack flue and recycling them over the oil heating tubes in admixture with the hot products of combustion from the fire-box. The forcing means shown is a steam jet but a fan or blower or other suitable forcing means may 100 be employed.

From the reservoir 8 the vapors escape through connection 14 and pass successively through two reflux towers 15 and 16 and thence to a condenser 17. The distillate is 110 condensed in the condenser and discharged into the receiver 18, whence condensate is drawn off through connection 19 and uncondensed vapors and gases through connection 20. In the reflux towers the 115 vapors are cooled and the heavier constituents refluxed by cool oil pumped about tubes therein. Fresh oil to be supplied to the operation is employed for this purpose. Where fresh oil is supplied to the reservoir 8 it is pumped through the reflux tower 15 in indirect heat exchanging relation with the vapors therein from connection 21 by means of pump 24 and is introduced into the shell or reservoir through 120 connection 25. Excess oil for cooling may be so pumped through tower 15 and the excess discharged through connection 26. In this way the refluxing operation may be regulated. The reflux tower 15 may however 125

be omitted. Fresh oil to be supplied to the single pass heater is pumped through the reflux tower 16 from connection 23 by means of pump 27 and is then introduced into the 5 single pass heater at an intermediate point through connection 6. The reflux from the tower 16, and from the tower 15 if employed, flows to the tank 28 where it is introduced into the first set of tubes 2 through connection 5 by means of pump 29. Additional oil may also be supplied to the first set of tubes through connection 22.

In operation a stream of oil is forced in a single pass through the heating conduit in 15 the heating furnace. Initially this stream is made up of refluxed oil and the fresh heating gases at highest temperature are first brought into contact with that part of the conduit through which the reflux is 20 circulating. The heating gases are thus reduced in temperature by the heat absorbed in this part of the conduit while at the same time this part of the conduit exposed to the most severe conditions is protected by the absorption 25 of heat in the relatively refractory reflux. Likewise, the relatively refractory reflux is here subjected to cracking conditions adapted to decompose it into the desired lighter products, and other more or less refractory stocks may also be supplied to this 30 part of the heating conduit with the reflux. Fresh oil is then supplied to the stream at an intermediate point and the heating is continued by heat exchange with the tempered 35 heating gases. As fresh oil is supplied to the stream it is in part heated by admixture with the reflux and the cracked reflux constituents and as this heat is supplied internally it does not increase the tendency to 40 deposition. The walls of the latter part of the conduit are thus further protected by being relieved of the burden of transferring the heat so supplied. By preheating the 45 fresh oil, for example by heat exchange with the cracked vapors, the heating tubes are further protected by relief from another part of the heating burden. The reflux may also be returned to the heating conduit at a 50 relatively high temperature. With the same size heating tubes, the rate of flow is increased as the volume of oil and cracked products flowing through the heating conduit increases. This may however be regulated by adjusting the relative size of the 55 heating tubes. The operation of the single pass heater as just described, as well as the operation of the remainder of the apparatus illustrated in Fig. 1, is pictorially represented in Fig. 2.

60 In the apparatus illustrated, the heating conduit discharges into a vaporizing drum or reservoir in which the vapors of the cracked oil are separated from any residue. The residue may be reduced to coke in this 65 reservoir or it may be withdrawn as a flux

through connection 30. External heat may be supplied to the vaporizing drum, but it may advantageously be heated internally only by the hot products discharged from the single pass heater. The temperature 70 conditions in the reservoir may also be regulated by supplying fresh oil thereto. Where the reservoir is heated internally only, or where only a small amount of heat is supplied externally for example enough 75 to make up for radiation losses, more easily cracked oils may advantageously be cracked therein by the heat supplied by the hot products discharged from the single pass heater. The apparatus illustrated is also flexible as 80 to pressure control. The pressure in the single pass heater may exceed that in the reservoir by just sufficient to maintain flow therethrough at the desired rate, or a substantially 85 higher pressure may be maintained in the heater. The pressure may also be reduced between the reservoir and the reflux towers or they may be operated in open communication. The pressure may also be reduced between the reflux towers and the condenser, or the pressure may be maintained 90 through the condenser and reduced at a point beyond the condenser. The actual pressures employed may vary widely. In the heater, pressures of from about 25 up to 300 pounds 95 per square inch or more may be employed and a similar range of pressures may be used in the reservoir.

Another advantage of the invention is that it provides an apparatus and a method 100 of operation in which a series of zones are provided in which cracking conditions of progressively decreasing rigor are maintained, and advantage may be taken of this feature of the invention in handling charging stocks of different character. In the production of gasoline in apparatus of the type illustrated, for example, the fresh oil supplied to the heating conduit at the intermediate point may be of a gas oil or kerosene character. The reflux initially supplied to the heating conduit will comprise the vaporized constituents heavier than suitable as components of the desired pressure distillate. Other light oils may also be initially supplied to the heating conduit in admixture with the reflux, for example where a gas oil character stock is supplied to the conduit at an intermediate point a kerosene, or light kerosene, character stock 110 may be supplied in admixture with the reflux. Heavy or easily cracked stocks may with advantage be supplied to the reservoir. For example, a heavy gas oil may be supplied to the reservoir. Pressure still tar or topped crude oils may also be introduced into the reservoir and cracked therein by the heat of the hot products discharged from the single pass heater.

115 In the production of gasoline or pressure 120

distillate from charging stocks such as those described above, the operation may be regulated so that the temperature of the oil discharged from the single pass heater is in the neighborhood of from about 700° to 1200° F. Where no heating gases are recirculated, the temperature of the fresh heating gases first contacting with the tubes may be as high as 2100° to 2700° F. Where 5 part of the heating gases are recirculated, for example as more particularly described in my application filed May 15, 1925, Serial No. 30,404 the temperature of the heating gases as they first contact with the tubes 10 may be reduced, for example to something in the neighborhood of 900° to 1500° F., while the efficiency of the operation is nevertheless maintained. By combining recirculation of part of the heating gases with the 15 improved way of supplying fresh oil and reflux to the single pass heater, as is contemplated in one aspect of the invention, the heating tubes of the single pass heater are further protected while providing an 20 improved and efficient cracking operation. 25

I claim:

1. An improved method of cracking hydrocarbon oils, which comprises circulating oil in a single pass through a heating conduit, heating the oil circulating through the 30 conduit to a cracking temperature by circulating heating gases thereover in generally concurrent relation with the oil flow, subjecting the vapors of the cracked oil discharged from the conduit to a refluxing operation, supplying reflux from the refluxing 35 operation to the conduit at a point adjacent the end of the conduit over which the heating gases first circulate, and supplying fresh oil to the conduit at an intermediate point.

2. An improved method of cracking hydrocarbon oils, which comprises circulating oil in a single pass through a heating conduit, heating the oil circulating through the 45 conduit to a cracking temperature by circulating heating gases thereover in generally concurrent relation with the oil flow, subjecting the vapors of the cracked oil discharged from the conduit to a refluxing operation, supplying reflux from the refluxing 50 operation to the conduit at a point adjacent the end of the conduit over which the heating gases first circulate, supplying fresh oil to the conduit at an intermediate point, and recirculating over the heating conduit part of the heating gases which have passed thereover in admixture with fresh heating gases.

55 3. An improved method of cracking hydrocarbon oils, which comprises circulating oil in a single pass through a heating conduit, heating the oil circulating through the 60 conduit to a cracking temperature by circulating heating gases thereover in generally

concurrent relation with the oil flow, subjecting the vapors of the cracked oil discharged from the conduit to a refluxing operation, supplying reflux from the refluxing 65 operation to the conduit at a point adjacent the end of the conduit over which the heating gases first circulate, preheating fresh oil, and supplying the preheated fresh oil to the conduit at an intermediate point.

4. An improved method of cracking hydrocarbon oil, which comprises circulating oil in a single pass through a heating conduit and thence into a reservoir, heating the oil circulating through the conduit to a cracking temperature by circulating heating 70 gases thereover in generally concurrent relation with the oil flow, taking off vapors of the cracked oil from the reservoir and subjecting them to a refluxing operation, supplying reflux from the refluxing operation 75 to the conduit at a point adjacent the end of the conduit over which the heating gases first circulate, and supplying fresh oil to the conduit at an intermediate point.

5. An improved method of cracking hydrocarbon oil, which comprises circulating oil in a single pass through a heating conduit and thence into a reservoir, heating the oil circulating through the conduit to a cracking temperature by circulating heating 80 gases thereover in generally concurrent relation with the oil flow, taking off vapors of the cracked oil from the reservoir and subjecting them to a refluxing operation, supplying reflux from the refluxing operation 85 to the conduit at a point adjacent the end of the conduit over which the heating gases first circulate, and supplying fresh oil to the conduit at an intermediate point.

6. An improved apparatus for cracking hydrocarbon oils, which comprises a heating furnace and a single pass heating conduit arranged therein, a reflux tower communicating with the discharge end of the heating conduit, means for supplying reflux from the said tower to the inlet end of the conduit, means for supplying fresh oil to the 90 conduit at an intermediate point, and a firebox communicating with the furnace at a point adjacent the supply end of the heating conduit.

7. An improved apparatus for cracking hydrocarbon oils, which comprises a heating furnace and a single pass heating conduit arranged therein, a reflux tower communicating with the discharge end of the heating 95 conduit, means for supplying reflux from the said tower to the inlet end of the conduit, means for supplying fresh oil to the conduit at an intermediate point, a fire-box communicating with the furnace at a point adjacent the supply end of the heating 100 conduit.

duit, and means for recirculating heating gases escaping from the furnace again over the heating conduit.

8. An improved apparatus for cracking hydrocarbon oils, which comprises a heating furnace, a reservoir, a single pass heating conduit arranged in the furnace and arranged to discharge into the reservoir, a reflux tower communicating with the vapor space of the reservoir, means for supplying reflux from the said tower to the end of the heating conduit opposite the discharge end, means for supplying fresh oil to the conduit at an intermediate point, and a fire-box communicating with the furnace at a point adjacent the supply end of the heating conduit.

9. An improved apparatus for cracking

hydrocarbon oils, which comprises a heating furnace, a reservoir, a single pass heating conduit arranged in the furnace and arranged to discharge into the reservoir, a reflux tower communicating with the vapor space of the reservoir, means for supplying reflux from the said tower to the end of the heating conduit opposite the discharge end, means for supplying fresh oil to the conduit at an intermediate point, a fire-box communicating with the furnace at a point adjacent the supply end of the heating conduit, and means for recirculating heating gases escaping from the furnace again over the heating conduit.

In testimony whereof I affix my signature.

EDWARD W. ISOM.
